(57) **CLAIM**

I claim the ornamental design for a wireless door lock rosette, as shown and described.

DESCRIPTION

FIG. 1 is a front view of a wireless door lock rosette. FIG. 2 is a perspective view of the wireless door lock rosette of FIG. 1.

FIG. 3 is a front view of the wireless door lock rosette of FIG. 1.

FIG. 4 is a first side view of the wireless door lock rosette of FIG. 1.

FIG. 5 is second side view of the wireless door lock rosette of FIG. 1 that is opposite the first side view of FIG. 4.

FIG. 6 is a top view of the wireless door lock rosette of FIG. 1; and,

FIG. 7 is bottom side view of the wireless door lock rosette of FIG. 1 that is opposite the view of FIG. 6.

The broken lines showing a door handle assembly in the Figures are for illustrative purposes only and form no part of the claimed design. The shade lines in the Figures show contour or the flatness of a surface, and not surface ornamentation.
